US00D704286S

(12) **United States Design Patent**
Yu

(10) **Patent No.:** **US D704,286 S**
(45) **Date of Patent:** **** May 6, 2014**

(54) **BALL HOLDER**

(76) Inventor: **Wan-Sheng Yu**, Taipei (TW)

(**) Term: **14 Years**

(21) Appl. No.: **29/371,636**

(22) Filed: **Jun. 17, 2011**

(51) **LOC (10) Cl.** **21-02**

(52) **U.S. Cl.**

USPC **D21/717**

Primary Examiner — Catherine Tuttle

CLAIM

(57) The ornamental design for a ball holder, as shown and described.

DESCRIPTION

FIG. 1 is a perspective view of the ball holder showing my new design, the inflating needles shown in broken lines being for illustrative purposes only, and forming no part of the claimed design;

FIG. 2 is a front view thereof;

FIG. 3 is a rear view thereof;

FIG. 4 is a left view thereof;

FIG. 5 is a right view thereof;

FIG. 6 is a top view thereof, the inflating needles shown in broken lines being for illustrative purposes only, and forming no part of the claimed design;

FIG. 7 is a bottom view thereof; and,

FIG. 8 is a perspective view showing the design in association with a ball, the ball and inflating needles shown in broken lines being for illustrative purposes only, and forming no part of the claimed design.

1 Claim, 6 Drawing Sheets
